DOOR KNOCKER

Edward J. Kunkel, Richmond, Calif., assignor to International Corporate Services, Richmond, Calif., a corporation of California

Filed Aug. 20, 1968, Ser. No. 13,203

Term of patent 14 years

Int. Cl. D8—03

U.S. Cl. D8—177

FIG. 3.

FIG. 1.

FIG. 2.

FIG. 4.

FIG. 5.

FIGURE 1 is a perspective view of a door knocker;
FIGURE 2 is a plan view of the door knocker shown in FIGURE 1;

FIGURE 3 is a top view of the door knocker shown in FIGURE 2;

FIGURE 4 is a side elevational view; and

FIGURE 5 is a bottom view of the door knocker shown in FIGURE 2.

The dominant features reside in the solid line portions.
I claim:

The ornamental design for a door knocker, as shown and described.
